UNITED STATES PATENT OFFICE.

JOHANN KÜBLER, OF BADEN, SWITZERLAND, ASSIGNOR TO AKTIENGESELLSCHAFT BROWN BOVERI & CIE., OF BADEN, SWITZERLAND.

METAL VAPOR RECTIFIER.

Application filed May 31, 1922, Serial No. 564,926, and in Switzerland June 11, 1921.

In metal vapor rectifiers it is usual to surround the anodes with casings for the purpose of preventing short circuits and back-ignitions. The lower opening of these casings extends into a zone of the interior of the rectifier vessel which is highly saturated with metal vapor.

In the case of a small load, or if an anode is cut out, it may readily occur that the metal vapor condenses on the anode because the pressure in the interior of the anode casing is higher than in the upper part of the rectifier vessel and the temperature of the anode may be too low.

In order to prevent condensation on the anode according to the present invention the anode casing is provided, in addition to the openings for the arc, at its lower end, with at least one lateral opening which leads to a strongly cooled point of the rectifier vessel either directly or by way of an attached pipe. The vapor will then flow from the casing to the said cooled point, and condensation on the anode will not so readily occur.

One embodiment of this invention is illustrated by way of example in the accompanying drawing which shows diagrammatically a section of a rectifier vessel.

As shown, the anode casing *a* is placed by means of the pipe *b* in communication with the cooled wall of the condensing chamber *c*.

What I claim is:—

1. A metal vapor rectifier including a cooled main vessel having a strongly cooled part, an anode and an anode casing open at its lower end and perforated near its upper end at a point adjacent to said strongly cooled part of said rectifier vessel.

2. A metal vapor rectifier as claimed in claim 1, including a pipe or duct leading from said perforated upper end of said anode casing to said strongly cooled part of the rectifier vessel.

3. A metal vapor rectifier as claimed in claim 1, including a pipe or duct leading from said perforated upper end of said anode casing to said strongly cooled part of the rectifier vessel, said strongly cooled part being constructed as an extended portion of the main cooled rectifier vessel.

In testimony whereof I have signed my name to this specification.

JOHANN KÜBLER.
